Primary Examiner — Clare E Heflin*(74) Attorney, Agent, or Firm* — Calfee, Halter & Griswold LLP(57) **CLAIM**

I claim the ornamental design for a lighting fixture, as shown and described.

DESCRIPTION

The single FIGURE is a perspective view of a lighting fixture showing the new design. Excluding the ornamental lattices, the fixture has mirror image symmetry about a vertical imaginary plane that bisects the fixture, and mirror image symmetry about a horizontal imaginary plane that bisects the fixture. The broken lines shown on the drawing depict portions of the light fixture that form no part of the claimed design.
